UNITED STATES PATENT OFFICE.

JOHN E. SCHANK, OF CHICAGO, ILLINOIS.

GOLF-BAG.

1,229,326.

Specification of Letters Patent. Patented June 12, 1917.

Application filed July 6, 1915. Serial No. 38,372.

To all whom it may concern:

Be it known that I, JOHN E. SCHANK, a citizen of the United States, and a resident of Chicago, in the county of Cook and State of Illinois, have invented certain new and useful Improvements in Golf-Bags, of which the following is a full, clear, and exact specification.

My invention is concerned with golf bags, and is designed to produce a device of the class described that shall have a bottom that will be simple in its construction, and yet extremely durable, notwithstanding the rough usage to which they are frequently subjected.

My invention is further concerned with a simple construction forming a *quasi* partition by which the wooden clubs may, in effect, be separated from the iron clubs, and their shafts protected from damaging contact with the adjacent heads of the iron clubs in the ordinary usage of the bag.

My invention is finally concerned with a novel construction whereby the bag will, with the clubs therein, readily stand erect on a fairly level green, so that if the player has to carry the bag himself, he can, with a little care, stand the bag upright while he is making his shot, thus obviating the necessity of stooping to pick up the bag after each shot.

To illustrate my invention, I annex hereto a sheet of drawings, in which the same reference characters are used to designate identical parts in all the figures, of which,—

Figure 1 is a perspective view of a bag containing my invention;

Fig. 2 is a central vertical section through the bottom thereof on an enlarged scale;

Fig. 3 is a plan view in section on the line 3—3 of Fig. 2;

Fig. 4 is a central vertical section through the reinforcing cap before it is put in place on the bag;

Fig. 5 is a top plan view illustrating the partition feature; and

Fig. 6 is a vertical section through the bottom of a bag thus equipped in section on the line 6—6 of Fig. 5.

The first feature of my invention is con-

cerned with the bottom of the bag, and the upper part thereof, as shown in Fig. 1, may be of any desired construction. If the body *a* is made of canvas, a customary material, I preferably sew to the outer face thereof a strip of leather *b* of sufficient thickness to furnish a substantial protection and reinforcement. This is preferably supplemented by a second reinforcing strip *c* of cardboard, interposed between the canvas and the leather, as clearly shown in Fig. 2, all three strips preferably extending to the bottom of the bag.

The novel element of my construction is the cap *d*, which is preferably made of some light metal, such as aluminum, or some other material having the same general characteristics. The cap is formed of the central disk-like portion *e*, which is preferably strengthened by forming therein the annular corrugations *f*, *f'* and *f''*. Extending downwardly from this body portion is the annular flange *g*, and at the bottom is the short horizontal flange or portion *h* connecting the flange *g* with the outer, upwardly extending flange *j*, which, as shown, is preferably about half the width of the flange *g*. When the parts are assembled, the material constituting the body of the bag and any reinforcing strips that may be employed, such as illustrated, are all extended down into the annular channel formed between the flanges *g* and *j*, and the flange *j* is rolled or crimped, or otherwise turned in, as shown in Fig. 2, so as to grip the body material between the two flanges. As it would be objectionable to have the ends of the shafts, or the heads, as the case might be, of the clubs strike against the metal of the bottom, I place over the upper surface of the bottom a heavy pad *k*, which may be of felt, or some similar suitable material or combination of materials, and which is preferably cemented in place on the top of the cap *d*, in the manner clearly shown in Fig. 2.

The second feature of my invention is concerned with a partition construction by which the wooden clubs may be held in the bag separate from the iron clubs, and in such a manner as to prevent the heads of

the iron clubs from coming into contact with the shafts of the wooden clubs, to the detriment of the latter.

With this end in view, I secure across the 5 top of the bag, at right angles to the handle *l*, a separating or partition strap *m*, which is preferably detachably secured to the inner walls of the top ring *n* by the fasteners *o*, which may be of the customary button 10 type used on over-all's, etc. At the bottom of the bag, and across the center and parallel to the general direction of the strap *m*, I secure a partition rib *p*, which preferably 15 takes the form of a sheet-metal bar shaped as shown, and which, when employed in connection with my novel metallic bottom, is secured on top of the felt pad *k*, preferably by the rivets *q* passing through the horizontal flanges *r* of the rib *p*. The top 20 of the rib is preferably inclined, substantially at the angle shown, so that the ends of the clubs will readily slide off of the same, and on one side or the other thereof.

In use, the wooden clubs will be inserted 25 above the strap on the side adjacent to the handle *l*, and their ends will rest above the partition *p* when the bag is carried by the shoulder strap or handle. The iron clubs are placed in the bag below the strap, and 30 with this arrangement, it will be apparent that the heads of the iron clubs will hang down over the edge of the bag, and that the heads of the wooden clubs will likewise hang down, but at a greater distance from 35 the mouth of the bag, and the shafts are held away from the heads of the iron clubs by the strap *m*, so that no damage is done by reason of unnecessary contact between them. The arrangement makes it possible 40 to withdraw the clubs from the bag more readily than where they are mixed indiscriminately, as is the case with bags where no partition is employed.

A very great advantage of my novel construction resides in the fact that with the 45 bottom of the bag elevated above the flange *h*, which alone strikes the ground, and which will readily sink into the short grass with which the greens are covered (while a 50 flat-bottom bag would not), the bag will stand erect and unsupported if set down carefully, thus enabling the golfer, if he has to carry the bag himself, to play his game without the necessity of stooping to 55 pick up his bag after every shot, as is necessary with the ordinary bag. The use of the partition *p* and the strap *m* also assists in securing this desired result, because they act to distribute the weight of 60 the clubs more uniformly throughout the bag than would be the case if they were not employed, and as a consequence the bag will stand erect with the weight of the clubs thus distributed, whereas it would

not if their weight was all concentrated 65 on one side of the bag, as would be the case if the partition and strap were not employed and the bag were carried by the handle *l* prior to setting it down.

While I have shown and described my 70 invention as embodied in the form which I at present consider best adapted to carry out its purposes, it will be understood that it is capable of modifications, and that I do not desire to be limited in the interpretation 75 of the following claims except as may be necessitated by the state of the prior art.

What I claim as new, and desire to secure by Letters Patent of the United States, 80 is:

1. In a golf-bag bottom, the combination with the body material, of a metallic bottom cap having a deep annular channel into which the body material extends, said channel having its upper edge contracted to clamp the body material and bottom cap together by pressing the body material directly between the two walls of the channel, and a cushion secured on the top of the 90 metal inside of the bag.

2. In a golf-bag bottom, the combination with the tubular body material, of a sheet-metal bottom cap composed of a disk having a downwardly turned flange, and an 95 upwardly turned flange connected thereto of lesser width pressed against the inclosed body material to clamp it between the two flanges, for the purpose described.

3. In a golf-bag bottom, the combination 100 with the body material, of a sheet-metal bottom composed of a disk having annular corrugations therein and a downwardly turned flange, and an upwardly turned flange connected thereto of lesser width 105 pressed against the inclosed body material to clamp it between the two flanges, for the purpose described.

4. In a golf-bag bottom, the combination 110 with the canvas body material *a*, of the outer reinforcing strip *b* sewed thereto at its upper edge, the inner reinforcing strip *c* interposed between the canvas *a* and the leather *d*, a sheet-metal bottom cap *d* having the flanges *g* and *j* for the purpose 115 described, and the cushion *k* secured on the top of the bottom cap.

5. As a new and useful article of manufacture, a reinforcing cap for golf-bag bottoms, consisting of a metallic disk having 120 a downwardly extending annular flange, and an upwardly extending annular flange of less width joined thereto and adapted to have its upper edge turned inward, substantially as and for the purpose described. 125

6. In a golf-bag, the combination with a body portion having a bottom with a rigid flange extending downward therefrom

for a considerable distance so as to form a support for the bag in its upright position without the bottom proper touching the ground, of a strap secured across the top 5 of the bag, and a rib secured in the bottom thereof, parallel to the strap, substantially as and for the purpose described.

In witness whereof I have hereunto set my hand and affixed my seal, this 1st day of July, A. D. 1915.

JOHN E. SCHANK. [L. S.]
